UNITED STATES PATENT OFFICE.

JAMES E. GILBERT AND GLENN W. HARRIS, OF CHICAGO, ILLINOIS, ASSIGNEES TO
GILBERT SLIP SHEETING MACHINE COMPANY, OF CHICAGO, ILLINOIS, A COR-
PORATION OF ILLINOIS.

MECHANICAL SHEET STOP FOR SMUT-SHEET MACHINES.

1,420,653.

Specification of Letters Patent. Patented June 27, 1922.

Application filed January 30, 1920. Serial No. 355,115.

To all whom it may concern:

Be it known that we, JAMES E. GILBERT and GLENN W. HARRIS, citizens of the United States, residing at Chicago, county 5 of Cook, and State of Illinois, have invented a certain new and useful Improvement in Mechanical Sheet Stops for Smut-Sheet Machines, of which the following is a specification.

10 Patent Number 966,739 to J. E. Gilbert, issued August 9, 1910, illustrates and claims a machine for taking care of sheets of printed or lithographed matter between the time they receive the impression of ink and 15 the time they are sufficiently dried to prevent offsetting when placed on a pile. Broadly speaking that machine includes the use of an intermittently moving and successively folding strip of cloth between 20 which successive sheets of printed paper are placed immediately on being printed, and in which they are carried until sufficiently dry to be automatically delivered from the machine, all as will more fully appear from the inspection of said patent.

In that machine a section of a continuous strip of cloth is temporarily stretched between supports during which time it is referred to as a "print sheet support." 30 While this section of cloth is being fed into position in the support the paper to be taken care of travels along and is carried by it to the position where it is to be "smutted" by the succeeding section of cloth. 35 When a print sheet support, either a section of cloth in the machine of said prior patent or a separate independent sheet, as is possible in other machines, is fed to a fixed position preparatory to smutting and paper 40 is carried by said print sheet support a difficulty arises in that the sheet of carried paper does not, unaided stop with the print sheet support in any accurately predetermined position. In fact, due to air currents, momentum, and other elements unnecessary to mention it is apt to take almost any sort of a position it chooses.

The object of this invention is to provide 50 mechanical means applicable both to moving print sheet supports generally carrying paper to a stopped position and more particularly to the print sheet support mechanism of said prior patent, which will as the print sheet support comes to rest, accu-

rately stop the sheet of paper and position 55 it on the print sheet support and for practical purposes hold it there until the covering smut sheeting is sufficiently in place so that external, temporary holding means is no longer required. The invention 60 consists in means for accomplishing these objects, which can be comparatively easily and inexpensively built, which is satisfactory in use and is not readily liable to get out of order. More in detail the invention 65 consists in many features and details of construction more fully set forth in the specification and claims.

Referring to the drawings in which like numerals denote like parts throughout the 70 several views,

Figure 1 is a side view of a modernized machine of the general character shown in said Gilbert patent, showing particularly and quite in detail the operating mechanism 75 for driving the two more or less independent parts of the mechanism of this invention.

Figure 2 is a reversed plan view of the machine shown in Figure 1.

Figure 3 is an enlarged detail view of 80 many of the essential operating parts of the machine as seen when the operator stands behind the structure of Figure 1 and looks toward it, this view being taken on the line 3-3 of Figure 2.

Figure 4 is a plan view of a folded section of the smut sheet material showing the manner in which a crossbar is attached thereto in the preferred form of construction. 85

Figure 5 is an enlarged detail view showing certain changed positions taken on the line 3-3 of Figure 2.

Figure 6 is a changed position view of 90 certain parts in Figure 3 showing particularly an auxiliary stop device taken on the line 6-6 of Figure 2.

Figures 7 and 8 are changed position views of the mechanism of Figure 6.

Figure 9 is a detail end view on the line 100 9-9, Figure 7.

Figure 10 is a detail view of a connection between lever 36 and wheel 44 which operates it.

A machine to which the device of this 105 invention in its preferred form is applied is mounted in a general frame 20, corresponding in general terms to that of said

Gilbert patent. The main frame 20 has mounted inside it four vertical slides, two at the front being designated 22 and two at the rear being designated 24, corresponding 5 in general function to the "channel irons 44 and 45" of the Gilbert prior patent. A continuous piece of cloth, heretofore referred to, and designated in Figure 1 by general numeral 26 is in performing the work of 10 smut sheeting folded into these slides as shown in Figure 1 and is temporarily retained therein by cross bars 28 entering the slots in said slides, as shown in various figures. The complete mechanism for handling the cloth as is done in said prior patent being unnecessary to illustrate the features 15 of this invention is only shown in the drawings in so far as is required to make the device of this invention clear.

20 Each cross bar 28 is pivoted on the cloth 26 at a predetermined point thereon through the use of a pivot rod or wire 30 running through a loop in the cloth and ears on the bar, the same being the subject 25 matter of another patent application, Serial Number 382,142, filed May 17, 1920.

In the general machine a suitably actuated continuously rotating power shaft 32 is provided for operating the various mechanisms which will be referred to in this application. The cloth 26 is, at the top of the machine, actuated in the general manner as set forth in the Gilbert patent through mechanism driven by shaft 32. Pivoted at 35 34 near the lower portion of the frame 20 and on opposite sides thereof are vertically extending parallel arms 36, each having in them an elongated slot 38 entered by a square sliding block 40 driven on a stud 42 40 fastened in the face of a rotatable disk 44 driven by shaft 32. Pivoted to the upper end of each lever 36 at 46 is a connecting rod 48 carrying at its opposite end one end of the cloth moving roller 50. Each end of 45 this roller is guided for approximate horizontal reciprocation by rollers 52 movable in a cam track 54. This cam track 54 and the lever mechanism 36 are the subject matter of a companion patent application, 50 Serial Number 370,261, filed March 31, 1920.

The lever mechanism 36 is so driven by shaft 32 that the roller 50 starts from a point somewhat to the left of that shown in Figure 3 to begin to fold in the cloth 26, and 55 thereafter moves successively through the positions of Figures 3, 5 and 7 to completely fold the cloth and insert an adjacent cross bar 28 in the front slides 22, as shown in Figures 7 and 8. Thereafter it withdraws 60 through the dotted line position of Figure 8 and then the full line position of Figure 8 to original position, all as more fully set in the original Gilbert patent.

The connection between the disk 44 and 65 the lever 36 is so arranged with relation to

the speed of the printing press to which the device is applied that the feeding of the cloth forward to the point where it is locked in the front slides occupies approximately 225° of the rotation of the disk 44 and the 70 return stroke requires approximately 135°, as will more fully appear in said companion application. These relative proportions are merely selected to conform to present press practice.

75 In correspondence with the description and terminology in said prior Gilbert patent that portion of the cloth 26 which, when the parts are in the position of Figure 3, carries the paper 56 to be smutted, is technically designated the "print sheet support" 80 and the portion of the cloth which follows it and is laid over that sheet of paper 56 for the purpose of smutting, is technically called the "smut sheet." Where occasion 85 occurs in the drawings for referring to these parts the print sheet support is designated 26^a and the smut sheet is designated 26^b.

90 The machine thus far described is so located that the printing press which delivers sheets of paper to the machine is on the left of all figures except Figure 1 and Figure 3 shows a sheet of paper 56^a just put in place on the print sheet support 26^a at the extreme left of that figure and ready to be carried 95 into the machine. As noted in the beginning the problem to be solved is to so arrange matters that when that paper finally is enclosed by the next following smut sheet it will be in a desired predetermined position in the machine such, for instance, as is shown by the regularly piled sheets of 100 paper 56, appearing in the center of Figure 3, borne upon by their adjacent smut sheets. In carrying out this result the mechanism 105 now to be described is used.

On each side of the upper portion of the frame of the machine, and adjacent to the point where the control of the paper is to take place, is mounted a plate 58 having extending horizontally of it a substantially straight horizontal cam track 60. Slidable in each one of these cam tracks is a block or crosshead 62, mounted on the end of a horizontal rod 64 on one of whose sides in 110 the particular case here illustrated the lower side, is cut a rack 68 meshing with gears 70 one on each side of the machine. These two gears are carried by a common shaft 72 which in turn carries at one end a pinion 115 74 meshing with the rack 76 on the end of a rod 78, driven through the agency of bell crank 80 which carries a roller 82 traveling on the face of cam 84 mounted on shaft 32, heretofore referred to. This cam moves 120 rod 78 and all attached parts described in one direction, while a suitably located spring 86 moves these parts in the opposite direction whenever the position of the cam permits such motion. The result of the con- 130

struction just described is that each complete rotation of shaft 52 causes each cross head 62 to make a complete reciprocation of its slot 60 at a time and in a manner for specific 5 purposes hereafter described.

Extending between these two oppositely disposed crossheads 62 and journaled therein is a rotatable shaft 88 carrying at suitable points along its length traveling stop fingers 90, two being shown in the particular case here illustrated, adapted when moved to proper position to engage the advancing edge of the sheet of paper carried by a moving print sheet support and control it as 10 hereafter described. On one or both ends of shaft 88 as the constructor may elect, is a lever arm 92 carrying at its end a cam roller 94 traveling in an irregularly shaped elongated cam slot 96 formed in a plate or 15 block 98. This cam slot 96 in the particular case here illustrated rises at its opposite ends 96^a and 96^b to different heights above the general level of the cam slot. The result of this irregular shape of cam slot 96 is that 20 as shaft 88 is reciprocated, by cross head 62, as heretofore described, it is also given a properly timed partial rotation or rocking movement to cause it to first assume the dotted line position of Figure 5 wherein 25 the fingers 90 are elevated so that the bar 28 which is just in advance of the sheet of paper to be controlled, can pass under the fingers 90. As soon as the bar has passed these fingers 90 the cam immediately lowers 30 the fingers in front of the paper on the advancing print sheet support immediately following the bar, whereupon the fingers and paper and print sheet support travel along together to the right in Figure 5 until 35 the full line position of Figure 5 is reached. In approaching this latter position the end 96^b of the cam slot has caused the fingers 90 to elevate themselves enough to allow the roller 50 to pass under them as it finishes 40 its stroke to the right and starts to go back as indicated in Figure 8. In other words this cam is so shaped that it maintains the ends of fingers 90 in engagement with the cloth on the advancing print sheet support 45 under all conditions except when there are obstructions and then the fingers automatically get out of the way of those obstructions, viz, the passing bar 28 of dotted lines, Figure 5, and the roller in extreme right 50 hand position of Figures 7 and 8.

As roller 50 is during the operation of moving the cloth into engagement with the front slides necessarily in between two horizontal portions of cloths, viz, a print sheet 55 support and its adjacent smut sheet, the roller necessarily until the parts reach the position of Figure 7, holding these two portions of cloth separated one from the other, and when the roller retires beyond the full 60 line position of Figure 8 the upper portion

of cloth necessarily drops down as is clearly indicated in Figure 8 a distance equal to the thickness of the roller 50. As the cam mechanism just described does not permit the fingers 90 to drop lower than substantially 70 the position shown in Figure 8, it is entirely obvious that they cease to control the paper 75 56 on the print sheet support which is being put in final position. It is therefore, necessary to provide an auxiliary paper stop for controlling the paper on the print sheet support during this period of drop from the position of Figure 7 to that of Figure 8. If this is not done the paper will slip to the right as viewed in Figures 7 and 8, sometimes clear over the top of the front slides 80 22, thus obstructing them and rendering the machine inoperative. The present desired control of the paper is obtained by mounting on the frame of the machine adjacent 85 to the front slides 22 a rock shaft 100 actuated by a crank arm 102 moved by a rod 104 controlled in one direction by a spring 106 and in the other direction by cam roller 108 traveling on the face of a suitably shaped 90 cam 110 on shaft 32. Roller 108 is partially controlled by being mounted on a lever arm 112 pivoted at 114 to the frame.

Rigidly mounted on shaft 100 are a pair of packer arms 116 which move between the 95 position of Figure 5 in which the cross bars 32 are free to move from the left over into position and ready to descend the front slide 22 to the positions of Figures 7 and 8 in which these packer arms press the cross bar 100 down into the front slides through which they operate as set forth in the said prior Gilbert patent. Rigidly mounted on shaft 100 are lugs 118. Adjacent to each such lug is a pivoted block 102 with arm 122 attached, 105 the latter adapted to engage the cloth 26 as needed, as hereafter described. These blocks 120 with attached arms 122 move by gravity downward from the dotted line of Figure 7 through full line position of Figure 7 to 110 the position of Figure 8, and are returned to dotted line position of Figure 7 by the member 118 engaging the adjacent block 120 when the shaft 100 is moved in a clockwise direction as viewed in Figure 7 under the 115 control of cam 110. The cam 110 is so proportioned and timed that the lever arms 122 and 116 occupy the full line position of Figure 8 all the time except when the roller 50 is depositing a cross bar in the front slides 120 during which period these levers are elevated as described so as to permit the passage of the cross bars.

In operating a machine of this type it is 125 obviously desirable, not to say necessary, that the roller 50 in traveling from its extreme left hand position as viewed for instance in Figure 3 to the final position where the cross bar is let into the vertical slides should come gradually to a stop. The cam 130

84 is therefore, carefully designed so that the traveling stop members 90, heretofore described, will move proportionately to this movement of the roller and will come into operative engagement with the paper in passing from the dotted line to the full line position of Figure 5, in a gentle manner without injuring the edge of the paper.

Having thus described our invention what 10 we claim as new and desire to secure by Letters Patent, is:—

1. In mechanism of the class described, a print sheet support, means for moving it through the machine to a desired stopping point, a stop finger for engaging the print sheet support to position paper thereon, and means operative only during the final portion of the movement of the print sheet support for moving said finger in the direction 20 of movement of the support and in unison therewith, for the purposes set forth.

2. In mechanism of the class described, a print sheet support, means for moving it through the machine to a desired stopping point, a stop finger for engaging the print sheet support to position paper thereon, and means for moving said finger in the direction of movement of the support and in unison therewith, and means retaining the 30 finger clear of the support until it is required to do its paper stopping work as the support and paper stop, for the purposes set forth.

3. In mechanism of the class described, a print sheet support, means for moving it through the machine to a desired stopping point, a stop finger for engaging the print sheet support to position paper thereon, and means operative only during the final portion of the movement of the print sheet support for moving said finger in the direction of movement of the support and in unison therewith, and means retaining the finger 40 clear of the support until it is required to do its paper stopping work as the support and paper stop, for the purposes set forth.

4. In mechanism of the class described, a print sheet support and mechanism for moving it through the machine to a desired stopping point, stop fingers pivotally and reciprocatively mounted, means reciprocating said fingers in unison with the print sheet support to position paper on the print sheet support as it stops, automatic means rotating 55 said fingers toward and from the print sheet support, as required during their reciprocating movement to avoid obstructions carried by the support adjacent to the fingers, and means for so simultaneously, automatically 60 moving the print sheet support and the fingers.

5. In mechanism of the class described, means for moving a print sheet support through the machine to a desired stopping point, means at a point on the print sheet

support for securing said support at said stopping point, paper engaging fingers traveling with the print sheet support during the latter portion of its movement as it approaches the stop position to engage paper 70 on the support and position it, as the support comes to rest, and automatic means moving the print sheet support and said fingers adapted to momentarily move said fingers out of engagement with the print 75 sheet support to allow said securing means to pass under the fingers and on to securing position, for the purposes set forth.

6. In mechanism of the class described, a print sheet support movable through the machine to a predetermined position of rest, securing mechanism for fastening the print sheet support in the last mentioned position, a stop finger carrying mechanism reciprocatable, generally parallel to the movement 85 of the print sheet support, during the last portion of its movement, fingers on said carrier mechanism pivotally mounted for movement into and out of engagement with the print sheet support, and a cam mechanism operated by the general movement of the machine which holds said fingers clear of the print sheet support until said securing mechanism has passed said fingers and then permits said fingers to engage the print 90 sheet support during the remainder of the movement of the finger carrying mechanism and the print sheet support to rest position.

7. In mechanism of the class described, a print sheet support movable through the machine to a predetermined position of rest, a supporting bar for fastening the print sheet support in the last mentioned position, a stop finger carrying mechanism reciprocatable, generally parallel to the movement 100 of the print sheet support during the last portion of its movement, fingers on said carrier mechanism pivotally mounted for movement into and out of engagement for the print sheet support, and a cam mechanism 105 operated by the general movement of the machine which holds said fingers clear of the print sheet support until said supporting bar has passed said fingers and then permits said fingers to engage the print sheet 110 support during the remainder of the movement of the finger carrying mechanism and the print sheet support to rest position.

8. In mechanism of the class described, a print sheet support and means for moving it through the machine to a predetermined stopping point, paper retaining fingers mounted for movement parallel with the support during the latter portion of its movement to rest position and other fingers 115 movable to engage the paper on the support and relieve the first fingers as the support comes to rest, and automatic means for moving the support and the two sets of fingers 120 in coordination with each other.

9. In mechanism of the class described, a print sheet support, means for moving it in one general direction, to a predetermined stopping point in the machine and for then 5 moving it at an angle to the first direction of motion to a final stopping point, paper retaining fingers movable in unison with the support during the latter portion of its first said movements to retain the paper 10 thereon, and another set of fingers movable to retain said paper in said position while said support makes its second movement, and means coordinating the movements of the support and said respective sets of fingers, for the purposes set forth. 15

10. In mechanism of the class described, a print sheet support, means for moving it in one general direction, to a predetermined stopping point in the machine and for then 20 moving it at an angle to the first direction of motion to a final stopping point, paper retaining fingers movable in unison with the support during the latter portion of its first said movements to retain the paper thereon, 25 and another set of fingers movable to retain said paper in said position while said support makes its second movement, means coordinating the movements of the support and said respective sets of fingers, a locking 30 bar carried by the forward end of the print sheet support, and means causing each of said sets of fingers to move so as to allow said bar to pass them before they begin their paper engaging functions. 35

11. In mechanism of the class described, a frame having a pair of vertical slides placed opposite each other, a print sheet support carrying a bar to be ultimately deposited in said slides movable from a point at an angle 40 to said slides, through the machine toward said slides, means carrying said print sheet support in said path to deposit said bar in said slides, a paper retaining finger mounted for reciprocation parallel to the line of movement of the print sheet support during that 45 portion of its stroke where it approaches said slides, means retaining said finger remote from said print sheet support until said retaining bar has passed the finger and 50 for then moving said finger into engagement with the print sheet support, means then moving said finger in unison with the support to position paper as the support reaches its final position, a supplemental set of fingers 55 pivotally mounted at a point adjacent to said slides and free of the movement of the print sheet support, means automatically moving said last mentioned fingers out of the path of travel of the print sheet support until 60 the bar has passed said finger, and reached the slides, means then allowing said finger to automatically move to retain the paper in position on the print sheet support, means withdrawing the print sheet support moving 65 means, while the last mentioned fingers re-

tain the paper on the print sheet support, and automatic mechanism coordinating the movements of the various parts of the machine.

12. In mechanism of the class described, 70 in combination with a frame, a generally straight cam track parallel with said frame, crosshead mechanism traveling in said cam track, fingers pivoted on said crosshead mechanism to swing angularly to the path 75 of travel of the crossheads, a shaft in the frame of the machine, at a point remote from the path of travel of said crossheads, a finger pivoted on said shaft for rotation therewith, a print sheet support, means for moving 80 said print sheet support from a point outside the machine, first in a path of travel parallel to the path of said crossheads, and ultimately in the path in proximity to the movement of said second fingers, and means 85 for coordinating the movements of the print sheet support and the two sets of fingers whereby a sheet of paper on the print sheet support is engaged and stopped by the first set of fingers, during the first movement of 90 the print sheet support and is held in place by the second set of fingers during the final movement of the print sheet support. 95

13. In mechanism of the class described in combination with a suitable supporting 95 frame, an endless belt of smut sheet material, mechanism for folding successive portions of belt into zig-zags, mechanism for detachably securing the ends of the zig-zags to said frame and mechanical fingers following the to be secured portions of the belt as they move to secured position for engaging and positioning a sheet of paper while said paper is carried by a portion of belt being secured in said zig-zag form. 100

14. In mechanism of the class described, in combination with a suitable supporting frame, an endless belt of smut sheet material, mechanism for folding successive portions of the belt into zig-zags, mechanism for detachably securing the ends of the zig-zags to said frame and mechanical fingers following the to be secured portions of the belt as they move to secured position for engaging and positioning a sheet of paper while said paper is carried by a portion of belt being secured in said zig-zag form, and means holding said fingers away from the belt while devices on the belt for securing the end of a given zig-zag into the frame are 110 passing said fingers to the frame for the purposes set forth. 115

15. In mechanism of the class described, a print sheet support, means for moving it through the machine to a desired stopping point and for then further moving it at an angle thereto, a stop finger meeting the print sheet support as it comes to said stopping point and following said print sheet support during said final movement, to retain 125 130

paper in desired position on the print sheet support during said final movement.

16. In mechanism of the class described, a print sheet support, means for moving it through the machine to a desired stopping point, and for then further moving it at an angle to said first direction of movement, a finger meeting said print sheet support, at said stopping point, means moving said finger with said print sheet support in unison with it during said second movement to position the paper on said print sheet support during said movement and means thereafter returning said finger to original position.
15. 17. In mechanism of the class described, a print sheet support, means for moving it through the machine to a desired stopping point, and means for thereafter moving it at an angle to said first movement, a finger engaging the print sheet support at the time it reaches said stopping point to position the paper thereon, means for moving said finger in unison with the print sheet support during said second movement to retain 25 the paper in the position thereon, mechanism retaining said finger clear of the print sheet support until it reaches said stopping point, means then moving said finger into engagement with the print sheet support and retaining it there during said second movement of the print sheet support, and means finally returning said finger to original position.

18. In mechanism of the class described, a print sheet support movable through the machine to a predetermined position of rest, and then movable at an angle thereto to a second position, means carried by the print sheet support for detachably fastening the print sheet support in said position of rest, and for guiding it during its movement to said last mentioned position, fingers pivotally mounted adjacent to the machine to swing to engage the print sheet support as it reaches said first mentioned position of rest and to move in contact with the support to said final position and a cam mechanism operated by the general movement of the machine to hold said fingers clear of the print sheet support until said fastening mechanism has passed said fingers toward said first position of rest and to then permit

said fingers to engage and follow the print sheet support during the remainder of its movement, as described.

19. In mechanism of the class described, a print sheet support movable through the machine to a predetermined position of rest, and then movable at an angle thereto to a second position, means carried by the print sheet support for detachably fastening the print sheet support in said position of rest, and for guiding it during its movement to said last mentioned position, fingers pivotally mounted adjacent to the machine to swing to engage the print sheet support as it reaches said first mentioned position of rest, and to move in contact with the support to said final position and a cam mechanism operated by the general movement of the machine to hold said fingers clear of the print sheet support until said fastening mechanism has passed said fingers toward said first position of rest and to then permit said fingers to engage and follow the print sheet support during the remainder of its movement, and a cam mechanism for finally returning said fingers to original position.

20. In mechanism of the class described, a relatively flat print sheet support, means for moving it at an angle to its principal plane, a stop finger meeting the print sheet support and following said print sheet support during said movement, to retain paper in desired position on the print sheet support during said movement.

21. In mechanism of the class described, a relatively flat print sheet support, means for moving it at an angle to its principal plane, a finger meeting said print sheet support, means moving said finger with said print sheet support in unison with it during said movement to position the paper on said print sheet support during said movement, and means thereafter returning said finger to original position.

In witness whereof we have hereunto subscribed our names.
